SHOCK ABSORBER FOR AERIAL DELIVERY
APPARATUS

Theophilus Parsons, Washington, D. C.

Application November 15, 1945, Serial No. 628,946

8 Claims. (Cl. 244—138)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to aerial delivery apparatus and more particularly to an apparatus for easing the landing of packages delivered from aircraft in flight.

At the present time it is a common practice to deliver urgently needed commodities of many kinds by airplane when the time is too short to permit delivery by other means of transportation or when the point to which delivery is to be made is remote and in accessible to other means of transportation. In the latter case, it may be impossible for the aircraft to land, and any packages which are to be delivered will have to be dropped while it is in flight. At the present time the shock of landing packages under such conditions is eased by landing the package with a parachute, by means of special packaging designed to absorb the shock of landing and usually by a combination of both. The high cost of this type of packaging, the time and effort involved in packing the articles to be delivered in these packages and the fact that even this special packaging is not sufficient to permit the aerial delivery of delicate or fragile articles without danger of injury upon landing has retarded the more widespread use of aerial delivery.

Accordingly, it is an object of my invention to provide a new and improved shock absorber for use in the aerial delivery of packages which is provided with a bumper resiliently connected to the package and adapted to contact the ground in advance of the package so that the shock of landing is absorbed by the bumper and the resilient connecting means.

Another object of the invention is the provision of a new and improved shock absorber for the aerial delivery of packages which is adaptable for use on packages of various sizes and shapes and which may be easily modified to make it adaptable for the delivery of packages of various weights.

A further object of the invention is the provision of a new and improved shock absorber for the aerial delivery of packages which is simple and sturdy in construction, compact and light in weight, inexpensive to manufacture and which may be used repeatedly.

These and other objects of the invention will become apparent from the following description and accompanying drawing in which Fig. 1 is a side elevational view of the aerial delivery ap-

2

paratus of my invention, showing the relative position of the bumper and package at the moment the bumper contacts the ground. Fig. 2 is a fragmentary perspective view of the package holding harness for my aerial delivery apparatus. Fig. 3 is a side elevational view of my aerial delivery apparatus at the time when the package being delivered contacts the ground, and Fig. 4 is a fragmentary perspective view of a modified form of harness.

Referring to the drawing wherein a simplified embodiment of my invention is shown, and more particularly to Figs. 1 and 2, it will be seen that the aerial delivery apparatus includes a harness 15 adapted to be secured about the package. In the form of the invention illustrated, this harness consists of a strap 10 constructed from leather, webbing or other suitable material and provided at one end with a buckle 11 for engaging along 20 the opposite end of the strap thus adapting it to be secured about packages of various sizes and shapes. Secured along a portion of the strap adjacent its free end is a ring or eyelet 12 which is adapted to be secured to the shroud lines 13 25 of a parachute 14 either by having the shroud lines directly connected to the ring 12 as shown in the drawing or by having the ring connected to a riser of conventional construction which in turn is connected to the shroud lines.

30 For delivering relatively small packages of light weight, a harness constructed as shown in the drawings and just described will be suitable, but for relatively heavy packages or for packages of large size, a harness consisting of several package encircling straps similar to strap 10, and secured together by means of cross-straps 15, will be necessary. Each of the package encircling straps in a harness of this type would preferably be connected to the shroud lines 13 of the parachute 14 by means of conventional risers 23.

Secured along the portion of strap which extends along the vertical side of the package is a plurality of eye bolts 16, three being shown in Fig. 2 of the drawing. These eye bolts are 45 adapted to loosely receive the upper end of an elongated rod-like bumper 17 of light weight metal or other suitable material which is provided with a head 18 engageable with the upper one of the eye bolts 16 to limit downward movement of the bumper when a package is descending. A resilient connection between the bumper 17 and the strap or harness 10 is provided by an elongated tension spring 19 which is connected at its lower end to a bracket 20 secured to the harness as indicated in Figs. 1 and 2 and at its upper

end is connected to the head 18 of the bumper. The lower end of the bumper rod 17 is provided with a weight 21 which is removably secured thereto so that the weight may be changed in accordance with the weight of the package being delivered for a purpose to be described herein-after.

In using the improved shock absorbing apparatus just described, the strap 10 is tightly secured about the package 22 with the bumper rod 17 extending vertically downwardly with respect to the package when the latter is held in the position it will assume while descending from an airplane after the parachute 14 has opened and with the ring 12 positioned on the upper side of the package. The weight 21 at the end of the bumper rod 17 tends to maintain the package in this position with the bumper vertical and reduces the amount of swaying which would otherwise occur so that the end of the bumper rod will contact the ground first and will be in a vertical position or only slightly canted therefrom. Upon striking the ground, the descent of the bumper rod 17 will be abruptly stopped, but since the package 22 is not rigidly secured to the bumper rod it will continue in its descent, traveling axially of bumper rod 17 (as shown in Fig. 3), and this continued downward movement of the package will be resisted by the spring 19 so that the descent of the package will be gradually eased instead of being abruptly stopped. For this reason, when the package strikes the ground, the shock to the contents of the package is not nearly as great as it would be in the absence of a bumper, and delicate or fragile articles of all kinds may be delivered from airplanes in flight with very little or no breakage.

Although I have described a single embodiment of the invention of simplified construction, it will be obvious that many modifications in the size, arrangement and construction of parts are possible. Therefore, I do not desire to have my invention limited to the specific embodiment described but desire to include therein all those modifications coming within the scope of the appended claims.

I claim:

1. A shock absorber for use in the free aerial delivery of packages comprising a harness adapted to be secured about a package to be delivered, a parachute for retarding the descent of said package, an elongated bumper rod and a weighted ground-contact member laterally of said harness and adapted to precede said package in its descent, and resilient means for resisting the continued downward movement of said package after said ground-contact member contacts the ground whereby after said ground-contact member contacts the ground, said package travels axially of said elongated bumper rod at a gradually decreasing pace and strikes the ground at a substantially decreased rate of speed.

2. A shock absorber for use in the free aerial delivery of packages comprising a harness adapted to be secured about a package, an elongated bumper rod and a weighted ground-contact member laterally of and longitudinally movable with respect to said harness and package, and resilient means connecting said bumper rod and harness for resisting relative movement therebetween whereby after ground contact of said ground-contact member said package travels axially of said bumper rod at a gradually decreasing pace and strikes the ground at a substantially decreased rate of speed.

3. A shock absorber for use in the free aerial delivery of packages comprising a harness adapted to be secured about a package, an elongated bumper rod laterally of said harness, said rod having a free end and being longitudinally movable with respect to said package, ground-contact means laterally of said harness for urging said bumper into position for contacting the ground in advance of said package upon the aerial delivery thereof, said means comprising a weight at the free end of said bumper rod, and resilient means connecting said bumper rod and harness for resisting relative movement therebetween whereby after ground-contact of said ground-contact means said package travels axially of said bumper rod at a gradually decreasing pace and strikes the ground at a substantially decreased rate of speed.

4. A shock absorber as set forth in claim 3 wherein means are provided for guiding the downward movement of said package with respect to said bumper rod.

5. A shock absorber for use in the free aerial delivery of packages comprising a harness adapted to be secured about a package, a parachute for retarding the descent of said package, an elongated bumper rod and a weighted ground-contact member laterally of said harness and secured to said harness in position to contact the ground in advance of said packages upon the aerial delivery thereof, means associated with said bumper rod and said harness for permitting relative movement of said bumper rod with respect to said harness, and resilient means for resisting relative movement between said harness and bumper rod after ground contact of said ground-contact member in the aerial delivery of said package, said package travels axially of said elongated bumper rod at a gradually decreasing pace and strikes the ground at a substantially decreased rate of speed.

6. A shock absorber for use in the free aerial delivery of packages comprising a harness adapted to be secured about a package, a parachute for retarding the descent of said package, an elongated bumper rod laterally secured to said harness in position to contact the earth in advance of said package upon aerial delivery thereof, means associated with said bumper rod and said harness for permitting relative movement of said bumper rod with respect to said harness, resilient means for resisting relative movement between said harness and bumper rod, a weight on the lower end of said bumper rod laterally of said harness for urging the same to project vertically downwardly with respect to said package during the descent thereof and for initially contacting the ground, whereby after ground contact of said weight said package travels axially of said elongated bumper rod at a gradually decreasing pace and strikes the ground at a substantially decreased rate of speed.

7. A shock absorber for use in the free aerial delivery of packages comprising a harness adapted to be secured about a package, a parachute for retarding the descent of said package, an elongated bumper rod secured to said harness laterally thereof, and a weighted ground-contact member associated with said rod laterally of said harness in position to contact the ground in advance of said package upon the aerial delivery thereof, means associated with said bumper rod and said harness for permitting relative movement of said bumper rod with respect to said harness, resilient means for resisting relative movement between said harness and bumper rod, and means for

guiding the vertical movement of said bumper rod, whereby after ground contact of said ground-contact member in the aerial delivery of said package, said package travels axially of said elongated bumper rod at a gradually decreasing pace strikes the ground at a substantially decreased rate of speed.

8. A shock absorber for use in the free aerial delivery of packages comprising a harness adapted to be secured about a package, an elongated bumper rod, means for securing bumper rod laterally on said harness, said means being adapted to permit longitudinal movement of said package with respect to said bumper rod, resilient means for resisting movement between said harness and said bumper rod, and a weighted ground-contact member on said elongated bumper rod laterally of said harness, whereby after ground contact of said ground-contact member in the aerial delivery of said package, said package travels axially of said elongated bumper rod at a gradually decreasing pace and strikes the ground at a substantially decreased rate of speed.
